(57) **CLAIM**

The ornamental design for a portion of a shoe upper, as shown and described.

DESCRIPTION

FIG. 1 is a perspective view of a portion of a shoe upper showing my new design;

FIG. 2 is a side view of one side thereof; and,

FIG. 3 is a top view thereof.

The uneven broken line showing the remainder of the shoe is for illustrative purposes only and forms no part of the claimed design. The uneven broken line immediately adjacent to the shaded area represents an unclaimed boundary of the design.
